UNITED STATES PATENT OFFICE

WILLIAM C. STEVENS AND CLARENCE T. EVANS, OF MILWAUKEE, WISCONSIN, AS
SIGNORS, BY MESNE ASSIGNMENTS, TO CUTLER-HAMMER, INC., A CORPORATION
OF DELAWARE

CIRCUIT CONTROLLER

Application filed November 26, 1923. Serial No. 676,914.

This invention relates to circuit controllers and while not limited thereto is particularly applicable to motor starters of the enclosed type.

5 The invention has among its objects to provide an improved motor starter of the enclosed type having its switch parts and starting resistance arranged in an exceedingly compact relation within a relatively small enclosing casing.

10 Another object is to provide a motor starter of the aforesaid character including a resistance element which is bendable to suit the space conditions between the switch mechanism and the enclosing casing and which, due to its inherent structure, will retain the form into which it is bent.

15 Another object is to provide a motor starter having a resistance element of the aforesaid character, such element being complete in itself and including terminal devices to be detachably secured to certain parts of the switch mechanism.

20 Another object is to provide a motor starter of the enclosed type including a resistance element of the aforesaid character which is arranged adjacent or in contact with a relatively large surface of the interior of the enclosing casing to provide for rapid transmission of heat from the element to the enclosing casing.

25 Various other objects and advantages of the invention will hereinafter appear.

The accompanying drawings illustrate a 30 motor starter embodying the invention but it should be understood that certain features of the invention are not limited to motor starters of the character shown but are capable of use in other relations.

35 In the drawings,

40 Figure 1 is a front elevational view of a motor starter embodying the invention, the cover of the enclosing casing being removed.

45 Figs. 2 and 3 are vertical sectional views on lines 2—2 and 3—3 respectively, of Fig. 1.

50 Fig. 4 is a horizontal sectional view taken substantially on line 4—4 of Fig. 1.

55 Fig. 5 is a side elevational view, on a reduced scale, of the enclosing casing and the operating member of the starter, and

Fig. 6 is a schematic view of the starter and the circuit connections therefor.

Referring to the drawings, the same illustrate a motor starter including switches 1 and 2, the former switch being adapted as herein-after set forth to control the continuity of the motor circuit and the latter being adapted to include and exclude a resistance element R in the armature circuit of the motor. The switches 1 and 2 are mounted upon an insulating panel 3, such panel being secured to the rear wall of an enclosing casing 4, and, as hereinafter set forth, the resistance element R is adapted to be mounted within a relatively small space between the switch mechanism and the enclosing casing and is supported by certain parts of the switch mechanism.

More specifically, switch 1 includes a stationary contact 5 mounted upon a supporting post 6 fixed to base 3, and a co-operating movable contact finger 7 arranged in front of said stationary contact and normally out of engagement therewith. Switch 2 includes a stationary contact 8 carried by a supporting bracket 9 fixed to base 3 and a co-operating movable contact finger 10 arranged to the rear of said stationary contact and normally engaging the same. Contact fingers 7 and 10 are mounted upon supporting members 11 and 12 respectively, and said supporting members are pivotally mounted upon a pin 13 carried by a U-shaped magnet frame 14 fixed to the front face of insulating panel 3. As best shown in Fig. 1, pin 13 is supported by spaced upwardly projecting lugs 15 and 16 on the front wall of magnet frame 14 and supporting member 11 is provided with spaced bearing portions 17—17 arranged on opposite sides of the former lug while supporting member 12 is provided with spaced bearing portions 18—18 arranged on opposite sides of the latter lug.

Also, as best shown in Figs. 2 and 3, supporting members 11 and 12 are provided with upwardly extending projections 19 and 20, respectively. Contact finger 7 has its lower end fulcrumed within a recess and the front face of extension 19 while contact finger 10 has its lower end fulcrumed within a recess in the rear face of extension 20 and each of

said contact fingers is yieldingly held in engagement with its respective supporting member by a spring pressure device 21 of conventional design.

5 Magnet frame 14 carries electromagnets 22 and 23, arranged vertically and in a plane parallel to the face of insulating base 3. Supporting member 11 is provided with a rearwardly extending armature projection 24 to be attracted by magnet 22 for retention 10 of switch 1 in closed position and supporting member 12 is provided with a rearwardly extending armature projection 25 to be attracted by magnet 23 for retention of switch 15 2 in open position. As hereinafter set forth, magnet 23 maintains switch 2 in open position during starting of the motor, but as soon as the motor is brought up to speed a spring 26 overcomes the restraining action of said 20 magnet and moves switch 2 to closed position. Spring 26 is held under compression between a projecting lug 27 on supporting member 12 and a cup member 28 carried by a screw 29, which is threaded into the lower wall of 25 magnet frame 14 and is adjustable for variation of the degree of compression of said spring. As shown in Figs. 1 and 3, the right hand bearing portion 18 of supporting member 12 has a projection 30 for engaging the 30 front face of magnet frame 14 to limit outward movement of said member and the contact finger carried thereby under the action of spring 26.

The operating means for switches 1 and 2 35 includes a cam member 31 fixed to a square shaft 32 by a cap member 33. Shaft 32 has one end journaled in the left hand wall of casing 4 and its opposite end fixed to an operating lever 35 having a hub portion 36 40 journaled in the right hand wall of said casing. As shown in Fig. 2, shaft 32 has a lever 37 fixed thereto and the same is biased to move in a clockwise direction by spring 38 having one end connected to said lever 45 and its opposite end connected to a pin 39 fixed to the lower wall of casing 4. Cam 31, as shown in Fig. 3, is provided with cam surfaces 40 and 41, the former surface being arranged to co-act with a forwardly projecting lug 42 on the left hand bearing portion 18 of supporting member 12 and the latter surface being arranged to co-act with a downwardly projecting lug 43 on the right hand bearing portion 17 of supporting member 11. 50 Referring to Fig. 5, it will be observed that the operating lever 35 has extreme "off" and "starting" positions and an intermediate "running" position. Upon movement of the lever 35 from its off to starting position cam 55 surface 40 engages lug 42 to move supporting member 12 and the contact finger 10 carried thereby into open position. Supporting member 12 is provided with a projecting lug 44 having an adjustable stop 44^a mounted 60 thereon and during movement of said mem-

ber and the contact finger 10 into open position said stop engages the upper face of a projection 44^b on supporting member 11 to move the latter in a direction for closure of contact finger 7. Contact finger 7 is retained 70 in closed position by magnet 22, and upon release of the operating lever 35 the latter is held in running position against the action of spring 38 through engagement of cam surface 41 with the lug 43 on supporting member 11. By forcibly moving lever 35 from its running position to its off position cam surface 41 acts on lug 43 to move supporting member 11 and contact 7 into open position 75 against the restraining action of magnet 22. 80

The function and operation of the afore-described starter will now be more fully set forth in connection with Fig. 6. The resistance element R, which will be hereinafter more fully described, has one terminal connected to stationary contact 5 of switch 2 and the other terminal thereof is connected to the movable contact element of said switch and also to the movable contact element of switch 1. As above set forth, upon movement of operating lever 35 from off position to starting position, the contact finger 7 of switch 1 is moved to closed position and the contact finger 10 of switch 2 is moved to open position. With the switches in this position the armature of the motor is connected across lines L and L' through switch 1 and resistance element R while the field of the motor is connected across said lines by a circuit extending through switch 1 and magnet 22. Upon release of the operating handle 35 switch 1 is held in closed position by magnet 22 while switch 2 is held in open position by magnet 23, the latter magnet being connected across the terminals of resistance element R. With magnet 23 connected in this manner it is apparent that the attractive force thereof decreases as the speed of the motor increases and spring 26 is adjusted to overcome the restraining action of said magnet to effect closure of switch 2 when the motor is brought up to a given speed. Closure of switch 2, excludes the resistance element R from the armature circuit of the motor. To stop the motor operating handle 35 is forcibly moved 115 from its running position to off position which movement effects opening of switch 1 as above described.

The resistance element R is supported by the switch mechanism, and, as shown in Fig. 1, the same comprises an elongated ductile tubular jacket or casing 45, terminals 46 and 47 inserted in opposite ends of said jacket and rigidly fastened thereto, a helical resistor 48 arranged within said jacket and connected to said terminals and insulation 49 compacted within the jacket and around and about the resistor. The terminals 46 and 47 are insulated from the jacket 45 and each of the same has a threaded shank provided with a pair of 125 130

- clamping nuts 50. The terminal 46 is secured to a projecting lug 51 on bracket 9 while terminal 47 is secured to a projecting lug 52 on magnet frame 14. The lugs 51 and 52 are provided with openings for receiving their respective terminals, said openings being slotted to permit ready removal of the element from the front of the casing. The resistance element is originally straight and is shaped to suit the space conditions between the switch mechanism and the enclosing casing. The element shown in the drawings is shaped to provide a looped portion arranged in a vertical plane and a looped portion arranged in a horizontal plane below the magnet frame 13. It is apparent that due to the inherent structure of the resistance element the same can be readily bent and upon bending will retain its shape. Furthermore, it should be noted that the element is self-supporting and capable of being readily installed. 5
- As shown in Fig. 1 the closing casing is of such dimensions that the right hand and bottom walls thereof are adjacent to the resistance element. Thus the heat generated in the resistance element will be rapidly transferred to the enclosing casing and it is to be noted that with an element of the aforescribed construction the casing can be brought into contact with the resistance element if desired. The enclosing casing is preferably formed in two parts consisting of a rear portion 4^a and a cover portion 4^b, said cover being arranged to carry the operating shaft 32 and lever 35 and being secured to the rear portion 4^a by screws 55. The rear portion 4^a of the enclosing casing is provided with an opening in the upper wall thereof for receiving the necessary conductors and the insulating base 3 is provided with suitable terminal devices 57 for connection to such conductors. 10
- As before stated, the switch 1 is adapted to break the motor circuit and in order to eliminate arcing between the contacts thereof, a magnetic blowout device is mounted upon the insulating panel 3. Such blowout device is of a conventional design and includes an electromagnet 58 fixed to insulating base 3 and having pole pieces 59 arranged on opposite sides of the contacts of switch 1. 15
- What we claim as new and desire to secure by Letters Patent is:
1. The combination with a circuit controller, of a closely fitting enclosing casing therefor, and a resistor for said controller comprising an insulated resistance wire enclosed within a long tubular sheath bent to lie between said controller and a plurality of the walls of said casing and in good thermal relation to the latter. 20
  2. The combination with a circuit controlling device, of a casing closely surrounding said device, and a resistor removably secured to said device and supported thereby, said re- 25
- sistor comprising an insulated resistance wire enclosed within a long tubular metal sheath bent to lie between said device and a plurality of the walls of said casing and in good thermal relation to the latter. 70
- In witness whereof, we have hereunto subscribed our names. 75
